UNITED STATES PATENT OFFICE.

HARRY A. SALLOP, OF NEW YORK, N. Y.

FURNITURE COVER.

Application filed March 2, 1928. Serial No. 258,544.

This invention relates to furniture covers and more particularly to the slip cover type used for protecting upholstered furniture and has for its primary object the provision of 5 a slip cover having an anti-slipping engagement with the furniture so as to assure the neat appearance thereof under all conditions.

An object of the invention is the association of a plurality of anti-slipping elements with 10 the various sections of the slip cover engageable with the surfaces of the furniture so as to prevent dislocation of the covers.

Another object of the invention is the utilization of a novel type of anti-slipping element engageable directly with the surface of 15 the furniture but mounted in a manner as to be invisible but capable of reinforcing the cover in a manner as to not detract from the attractiveness thereof.

20 A feature of the invention is the direct application to the under surface of the seat cover of a plurality of anti-slipping strips having resilient properties for accomplishing effective engagement between the surfaces of the 25 elements and the surface of the article of furniture to prevent displacement of the cover.

Besides the above, my invention is distinguished in the use of a seat pad or cover 30 incorporating a novel type of anti-friction element so arranged and disposed that the usual attaching elements for the pad are absolutely dispensed with.

With these and other objects in view, the 35 invention will be better understood from the following detailed description taken in connection with the accompanying drawings, wherein:

Figure 1 is a perspective view of an article 40 of furniture to which my improved type of slip cover is applied,

Figure 2 is a fragmentary sectional view,

Figure 3 is a detailed cross sectional view on the line 3—3 of Figure 2,

45 Figure 4 is a fragmentary view of a modification of the invention,

Figure 5 is a sectional view on line 5—5 of Figure 4,

Figure 6 is a perspective view of an in- 50 dividual seat cover or pad,

Figure 7 is a bottom plan view,

Figure 8 is a cross sectional view on line 8—8 of Figure 7, and

55 Figure 9 is a sectional view on line 9—9 of Figure 7,

Figure 10 is a rear view of a chair with a cover applied thereto.

Again referring to the drawings illustrating two of the many constructions of my invention, and more particularly to Figures 1 to 6 inclusive, it will be noted that the slip cover is of the usual design including side sections 1, a back section 2 and a seat section 3, cut to have a snug interfitting connection with the article of furniture and positively held in this neat appearance by a novel arrangement of anti-slipping elements now to be described and forming a part of my invention. In this particular case I have illustrated the anti-slip elements 4 attached to the seat section 3 but I wish it to be understood that these elements may be interposed wherever desirable to prevent shifting of the material of the slip covers. The anti-slip elements in this particular showing are in the form of a strip 5 embodying in its construction a plurality of lengths of rubber 6, arranged in exposed position so as to yieldably and frictionally engage the surface of the article of furniture. The strips 5 preferably of fabric material are directly sewed to the under surface of the section 3 as indicated at 7 and extend completely across the section 3 in parallel relation thereby co-functioning to positively prevent shifting or slipping of the seat cover and accomplishing this desired result without in any way interfering with the neat appearance of the cover or damaging or marring the surface of the furniture.

In Figures 2 and 3 I have illustrated the lengths of rubber 6 arranged upon the surface of the strip in spaced parallel relation so as to have individual gripping engagement with upholstery of the furniture but it may be found advantageous in practice from an economical standpoint to completely cover the surface of the strip with composition material, such as the commercially known sponge rubber designated by the numeral 8 in the Figures 4 and 5. I am aware of the fact that slip covers have been heretofore manufactured in standard sizes for commercial purposes and anti-slip elements utilized to prevent slipping of various articles but I am not aware of a new article of manufacture the success of which is dependent upon the combination of a slip cover section and a plurality of anti-slipping elements associated therewith for producing a new result,

namely, the nonslipping or displacement of slip covers out of their proper positions when applied to an article of furniture.

In Figures 6 to 9 inclusive of the drawing, 5 I have illustrated an individual type of seat cover commercially known as a seat pad incorporating anti-slipping elements so that the pad may be effectually held in contact with the surface of the seat in a manner to 10 dispense with the usual attachment elements such as straps utilized in securing seat pads to a chair. This improved type of seat cover comprises a pad 9 cut into the proper configuration to cover the surface of the seat 15 and preferably cut from fabric material with its edge portion materially reenforced and protected by a reenforcing strip 10 which may be of any suitable design and material to add to the ornamentation and attractiveness 20 of the seat cover. To the under surface of the pad is secured a plurality of anti-slipping elements 11 which may be of a construction similar to that heretofore described so as to have resilient properties for yieldable frictional engagement with the top surface of 25 the seat. Referring to Figure 7, it will be noted that the strips or anti-frictional elements 11 are arranged in group formation and angularly disposed so that the proper resistance will be offered to the displacement of the 30 seat cover in any direction. I wish to call attention to the fact that the end portions of the strip 11 are effectively secured under the reenforcing strip 10 in the sewing of the component parts together and thus a very substantial article is produced of a very neat appearance wherein the anti-friction elements 35 when in use are completely hidden from view.

From the foregoing description taken in 40 connection with the accompanying drawings, it will be appreciated that I have provided a type of slip cover or seat pad that will have an effective anti-slipping engagement with the surface of an article of furniture to pre-

vent shifting or slipping of a cover or pad 45 accomplished by the combination and arrangement of elements that will not interfere in any way whatsoever with the neat appearance of the article and which may be economically manufactured. It is of course 50 to be understood that various other types of anti-friction elements may be utilized with the covers and they may have resilient or non-resilient properties depending upon the results to be obtained and the requirements of 55 the trade and besides the articles may be used for various other purposes than shown in the drawings and, therefore, I do not desire to be limited in protection in any manner whatsoever except as set forth in the following 60 claims.

I claim:

1. As a new article of manufacture, in combination, a slip cover, having a back, side and seat section and anti-slipping elements 65 secured to the inner surface of the slip cover, each consisting of a strip directly sewed to said bottom section, and a plurality of yieldable elements supported in spaced relation by said strip.
2. In combination, a slip cover carrying a plurality of anti-slipping devices secured to the inner surface of this cover, consisting of a fabric strip directly sewed to the slip cover to extend in a predetermined direction, and 75 a plurality of lengths of rubber directly attached to the strip, to be located in spaced parallel relation with each other.
3. In combination, a slip cover, a plurality 80 of strips, directly sewed to the interior surface of the slip cover and in parallel spaced relation and a plurality of lengths of rubber secured to the surface of each strip to project beyond the surface of the strip in parallel 85 relation with each other.

In testimony whereof I affix my signature.

HARRY A. SALLOP.
